COMBINED KNOB FOR GEAR SHIFTS AND CIGARETTE LIGHTER

Leon E. Holloway, Anaheim, Calif.

Application February 4, 1950, Serial No. 7,733

Term of patent 14 years

(Cl. D14—6)

To all whom it may concern:

Be it known that I, Leon E. Holloway, a citizen of the United States, residing at Anaheim, in the county of Orange, State of California, have invented a new, original, and ornamental Design for a Combined Knob for Gear Shifts and Cigarette Lighter, of which the following is a specification, reference being had to the accompanying drawing, forming a part thereof.

Figure 1 is a top plan view of the combined knob for gear shifts and cigarette lighter embodying my new design;

Fig. 2 is a view in side elevation of the combined knob for gear shifts and cigarette lighter, the parts thereof being shown in separated position;

Fig. 3 is a view in end elevation and may be

regarded as taken upon the line 3—3 upon Fig. 2; and

Fig. 4 is a view in end elevation and may be regarded as taken upon the line 4—4 upon Fig. 2.

The dotted line showing in Fig. 1 is for illustrative purposes only.

I claim:

The ornamental design for a combined knob for gear shifts and cigarette lighter, as shown and described.

LEON E. HOLLOWAY.
